12 Claims. (Cl. 236—1)

This invention relates generally to zone temperature control systems and more particularly to an improved temperature control apparatus for use with a hot water heating installation for maintaining predetermined temperature conditions in each of a plurality of zones under thermostatic control.

In zone controlled heating installations in which heat is furnished from a common hot water boiler to a plurality of zone areas, the heating unit is generally of a size sufficient to supply heat to each zone area simultaneously to maintain all of the zone areas at a given temperature or temperatures during all anticipated weather conditions.

Very frequently, however, and particularly during weather which is not severe, heat is supplied intermittently rather than continuously to the various zones.

Thus, if all the zones require heat simultaneously the furnace associated with the hot water boiler will become operative to supply heat to each zone area. Unfortunately, however, the furnace will also become operative when only one zone area calls for heat. Obviously, the demand for heat from less than the total number of zones results in heat requirements which are considerably less than the operating capacity of the boiler output.

It is an object of this invention to provide an improved apparatus for controlling the operation of the heating system in a multi-zone area.

It is also an object of this invention to provide an improved heating system in a multi-zone area which can increase the temperature of a zone without requiring operation of the furnace burner of a heating unit.

It is another object of this invention to provide an improved apparatus which will provide increased economy in the operation of a heating system of a multi-zone area.

It is still another object of this invention to provide an improved apparatus which is reliable in operation and economical to build.

Other objects and many of the attendant advantages of this invention will be readily appreciated as the apparatus becomes better understood by reference to the following detailed description when considered in connection with the accompanying drawing wherein the figure is a schematic of structure in accordance with the principles of the invention.

Briefly, in this invention, a master zone and another or second zone are maintained at predetermined temperatures by means of a hot water heating installation operating under the control of a thermostatic switch. Immediately upon the closing of the contacts of the thermostat associated with the master zone the burner of a hot water heating unit, the zone valve and the circulation pump become operative. Upon the closing of the contacts of the second zone thermostat, the second zone valve becomes operative immediately, however, the operation of the burner of the hot water heating unit is delayed for a predetermined interval of time as determined by a delay means. Therefore, activation of the first or master zone thermostat results in immediate operation of the burner to heat the water in the boiler which is circulated by the circulation pump through the zone valve and the heat exchanger in the first zone. Activation of the second zone thermostat results in the immediate operation of the second zone valve to permit the water from the boiler to flow through the heat exchanger in the second zone and the immediate operation of the circulation pump to move

2

the water through the heat exchanger. Activation of the second zone thermostat does not result in the immediate operation of the burner of the hot water heating unit. A delay means is provided to delay the operation of the burner for a predetermined interval of time. Therefore, when the contacts of the second thermostat close the heat that is fed to the second zone is that residual heat which is present in the water. Under ordinary circumstances, the residual heat present in the water is sufficient to increase the temperature of the second zone to that of the thermostat setting before the expiration of the predetermined interval of time for which the delay means is set, and the contacts of the thermostat will open prior to the activation of the burner. If, however, the temperature of the second area is not raised to the setting of the thermostat within the predetermined interval of time for which the delay means is set, then the contacts of the thermostat will not open and the boiler burner will be activated and remain so until the temperature of the second zone is at least that of the thermostat setting. If an area has more than a first and second zone, then all zones other than the first or master zone are connected to operate in a manner similar to that of the second zone.

Referring now to the figure there is shown a three zone temperature control hot water system incorporating the principles of the invention. A first or master zone 10 incorporates a temperature sensitive means such as a thermostat control 12 or the like and a heat exchanger 14; a second zone 17 incorporates a temperature sensitive means such as a thermostatic control 16 or the like and a heat exchanger 18; a third zone 20 incorporates a temperature sensitive means such as a thermostatic control 22 or the like and a heat exchanger 24.

A hot water boiler 26 having a water outlet 28, a water inlet 30 and a burner unit 32 has a heating capacity which is sufficient to provide heat for each of the zones 10, 15 and 20 simultaneously. The water outlet 28 is connected, in shunt, through each of the heat exchangers 14, 18 and 24 to the water inlet 30. A circulation pump 34 is connected to move the hot water from the boiler 26 through the heat exchangers 14, 18 and 24 and then back to the boiler. Fluid control means such as zone valves operate electrically to permit or retard the passage of a fluid such as water or the like are provided to permit or prevent the flow of water through the heat exchangers. Zone valve 36 is positioned to permit or retard the flow of water through heat exchanger 14; zone valve 38 is positioned to permit or retard the flow of water through heat exchanger 18; and zone valve 40 is positioned to permit or retard the flow of water through heat exchanger 24.

A source of potential connected to feed the input terminals 44 and 46 of a step-down transformer 48, to the input terminals of a relay unit 42 and to the input terminals of a relay unit 43. The transformer 48 supports two output terminals 50, 52, terminal 50 being connected to a ground terminal and terminal 52 being connected to a contact of each of the thermostat control units 12, 16 and 22.

The contact 13 of thermostat 12 is coupled to feed a signal to the zone valve 36, the relay unit 43 associated with the water circulation pump 34 and the relay unit 42 associated with the burner unit 32.

The feeding of a signal from any of the thermostats to relay unit 42 activates the burner 32 and the feeding of a signal from any of the thermostats to relay unit 43 activates circulation pump 34. A signal fed to a zone valve 36, 38, 40 urges the valve to assume a position which will not retard the flow of water. Naturally, termination of the signal from the thermostat results in the stopping of the operation of the burner 32 and circulation pump 34, and the zone valve or valves activated assume a position which will retard the flow of water.

The contact 15 of the thermostat 16 is coupled to feed a signal to the zone valve 38, to the relay unit 43 of the water circulation pump 34 and to relay unit 42 of the burner 32 through a delay means 54.

The contact 21 of the thermostat 22 is coupled to feed a signal to the zone valve 40, to the relay unit 43 of the water circulation pump 34 and to the relay unit 42 of the burner through a delay means 55.

In some instances it may be desirable to incorporate the two delay means 54, 55 into a single delay means 57.

In operation, a source of potential is coupled to the terminals 58, 60 to feed a signal to the relay unit 42, to the relay unit 43 and through the step down transformer 48 to the thermostats 12, 16 and 22. Now, it is assumed that the temperature in zone 10 drops below the temperature setting of the thermostat 12 to cause the contacts of the thermostat to close. A signal is fed through the thermostat 12 to zone valve 36, to the relay unit 43 of the water circulation pump 34 and to the relay unit 42 of the burner 32. The zone valve 36 operates to permit water to flow through the heat exchanger 14. The relay unit 43 is energized and operates the circulation pump 34 which pumps hot water from the boiler 26 through the heat exchanger 14 and then back to the boiler 26. The relay unit 42 is energized and operates burner 32 which heats the water in the boiler 26. The burner 32 can be either of the oil or gas type. Thus, immediately upon the closing of the contacts of the thermostat 12 the burner 32 is activated and heats the water in the boiler 26 which is pumped through to the heat exchanger 14.

If, however, it is assumed that the temperature in zone 17 drops sufficiently to cause the contacts of thermostat 16 to close, then a signal is fed through thermostat 16 to zone valve 38, to the relay unit 43 which is then energized and operates the water circulation pump 34 and the delay means 54. The zone valve 38 operates to permit the passage of water and the circulation pump 34 is activated and pumps hot water from the boiler 26 through the heat exchanger 18 and then back to the boiler 26. The signal fed through the thermostat 16 also activates the delay means 54 which, after a predetermined interval of time, feeds a signal through to the relay unit 42 to energize the burner 32. Thus, when the contacts of the thermostat 16 first close, the heat transferred to the heat exchanger is that residual heat which is present in the water. The burner is not operative and no additional heat is supplied to the water. If, after a predetermined interval of time as determined by the setting of the delay means the residual heat present in the water has not been sufficient to raise the temperature of the zone above that for which the thermostat is set, then a signal is passed by the delay means to the relay unit 42 and the burner 32 is activated. In practice it has been found that this invention operates in a very satisfactory manner if the delay means is preset to provide a delay interval of time from 10 to 20 minutes. Thus, upon the closing of the contacts of the thermostat 16, hot water is circulated through heat exchanger 18, but the burner is not activated. This condition continues for that interval of time for which the delay means is set. If the temperature in the zone is increased to the setting of the thermostat prior to the termination of the time for which the delay means is set, then the contacts of the thermostat will open and prevent operation of the burner. However, if at the end of that period of time for which the delay means is set the thermostat contacts are still closed, then the burner becomes operative and supplies heat to the water.

In practice when using structure in accordance with the principles of this invention it has generally been found that the residual heat in the water is sufficient to raise the temperature of the zone an amount which is sufficient to satisfy the thermostat 16 before the burner becomes operative.

Thus, it is possible to supply heat to an area without requiring the activation of the burner. In those instances where the thermostat is not satisfied within the time interval for which the delay means is set, then the burner begins to operate and supplies the additional heat required to satisfy the thermostat, and the occupants of the zone do not experience any discomfort and, in all instances also are not even aware of the delay in the operation of the burner.

The operation of the structure of and that associated with zone 20 operates in the same manner as the structure of and associated with zone 17.

Thus, restating, when the thermostat of zone 10 indicates a need for more heat—the burner becomes operative immediately. However, when the thermostat of zones 17 or 20 indicate a need for more heat—the burner remains inoperative for a time duration equal to the time delay of the delay means if the residual heat present in the water being recirculated is not sufficient to raise the temperature of the zone to that for which the thermostat is set. Naturally, if the zone reaches the temperature for which the thermostat is set prior to the passing of a signal through the delay means to activate the burner—the thermostat contacts will open and the burner will not be activated. Continuing, a demand for more heat by zone 10 will cause the burner to become activated regardless of the operating condition of zones 17 and/or 20; and a demand by zone 20 for more heat after zone 17 has indicated a need for more heat means that zone 17 will control the time of activation of the burner 32.

Obviously many modifications and variations of the present invention are possible in the light of the above teachings. It is therefore, to be understood that within the scope of the appended claims the invention may be practiced otherwise than as specifically described.

What is claimed is:

1. A zone temperature control system comprising a first zone; a first heat exchanger in said first zone; a second zone; a second heat exchanger in said second zone; a fluid moving means; means coupled to said fluid moving means to feed a fluid along a first path to said first heat exchanger and along a second path to said second heat exchanger; first fluid control means to control the flow of the fluid through said first heat exchanger; second fluid control means to control the flow of the fluid through said second heat exchanger; heating means to heat said fluid; a first temperature sensitive means for detecting the temperature in said first zone coupled to said first fluid control means, said fluid moving means and said heating means; a second temperature sensitive means for detecting the temperature in said second zone coupled to said second fluid control means, said fluid moving means and said heating means; and delay means interposed between said second temperature sensitive means and said heating means to delay the operation of said heating means for a preselected interval of time.

2. A zone temperature control system comprising a first zone; a first heat exchanger in said first zone; a second zone; a second heat exchanger in said second zone; a water circulation pump; means coupled to said water circulation pump to feed water along a first path to said first heat exchanger and along a second path to said second heat exchanger; first fluid control means to control the flow of the water through said first heat exchanger; second fluid control means to control the flow of the water through said second heat exchanger; heating means to heat said water; a first temperature sensitive means for detecting the temperature in said first zone coupled to said first fluid control means, said water circulation pump and said heating means; a second temperature sensitive means for detecting the temperature in said second zone coupled to operate said second fluid control means, said water circulation pump and said heating means; and delay means interposed between said second temperature sensitive means and said heating means to delay the operation

of said heating means for a preselected interval of time.

3. A zone temperature control system comprising a first zone; a first heat exchanger in said first zone; a second zone; a second heat exchanger in said second zone; a water circulation pump; means coupled to said water circulation pump to feed water along a first path to said first heat exchanger and along a second path to said second heat exchanger; a first valve to control the flow of water through said first heat exchanger; a second valve to control the flow of water through said second heat exchanger; a burner to heat said water; a first thermostat for detecting the temperature in said first zone coupled to said first valve, said water circulation pump and said burner; a second thermostat for detecting the temperature in said second zone coupled to said second valve, said water circulation pump and said heating means; and delay means interposed between said second thermostat and said burner to delay the operation of said burner for a preselected interval of time.

4. A zone temperature control system comprising a first zone; a first heat exchanger in said first zone; a second zone; a second heat exchanger in said second zone; a boiler containing water; a water circulation pump coupled to said boiler; means coupled to said water circulation pump to feed water along a first path to said first heat exchanger and along a second path to said second heat exchanger; a first remotely controlled valve to control the flow of water through said first heat exchanger; a second remotely controlled valve to control the flow of water through said second heat exchanger; a burner to heat said water in said boiler; a first thermostat for detecting the temperature in said first zone coupled to said first remotely controlled valve, said water circulation pump and said burner; a second thermostat for detecting the temperature in said second zone coupled to said second remotely controlled valve, said water circulation pump and said heating means; and delay means interposed between said second thermostat and said burner to delay the operation of said burner for a preselected interval of time after operation of said second thermostat and said second remotely controlled valve and water circulation pump.

5. A zone temperature control system comprising a first zone; a first heat exchanger in said first zone; a second zone; a second heat exchanger in said second zone; a fluid moving means; means coupled to said fluid moving means; means coupled to said fluid moving means to feed a fluid along a first path to said first heat exchanger and along a second path to said second heat exchanger; first fluid control means to control the flow of the fluid through said first heat exchanger; second fluid control means to control the flow of the fluid through said second heat exchanger; heating means to heat said fluid; a first temperature sensitive means for detecting the temperatures in said first zone coupled to operate said first fluid control means, said fluid moving means and said heating means; a second temperature sensitive means for detecting the temperature in said second zone coupled to said second fluid control means; said fluid moving means and said heating means; and delay means preconditioned to pass a signal from 10 to 20 minutes after activation interposed between said second temperature sensitive means and said heating means to delay the operation of said heating means.

6. A zone temperature control system comprising a first zone; a first heat exchanger in said first zone; a second zone; a second heat exchanger in said second zone; a water circulation pump; means coupled to said water circulation pump to feed water along a first path to said first heat exchanger and along a second path to said second heat exchanger; a first fluid control means to control the flow of water through said first heat exchanger; second fluid control valve means to control the flow of the water through said second heat exchanger; heating means to heat said water; a first temperature sen-

sitive means for detecting the temperature in said first zone coupled to said first fluid control means, said water circulation pump and said heating means; a second temperature sensitive means for detecting the temperature in said second zone coupled to operate said second fluid control means, said water circulation pump and said heating means; and delay means preconditioned to pass a signal from 10 to 20 minutes after activation interposed between said second temperature sensitive means and said heating means to delay the operation of said heating means.

15 7. A zone temperature control system comprising a first zone; a first heat exchanger in said first zone; a second zone; a second heat exchanger in said second zone; a water circulation pump; means coupled to said water circulation pump to feed water along a first path to said first heat exchanger and along a second path to said second heat exchanger; a first valve means to control the flow of water through said first heat exchanger; a second valve means to control the flow of water through said second heat exchanger; a burner coupled to heat said water; a first thermostat for detecting the temperature in said first zone coupled to said first valve, said water circulation pump and said burner; a second thermostat for detecting the temperature in said second zone coupled to said second valve, said water circulation pump and said heating means; and delay means preconditioned to pass a signal from 10 to 20 minutes after activation interposed between said second thermostat and said burner 20 to delay the operation of said burner.

35 8. A zone temperature control system comprising a first zone; a first heat exchanger in said first zone; a second zone; a second heat exchanger in said second zone; a boiler containing water; a water circulation pump coupled to said boiler; means coupled to said water circulation pump to feed water along a first path to said first heat exchanger and along a second path to said second heat exchanger; a first remotely controlled valve to control the flow of water through said first heat exchanger; a second remotely controlled valve to control the flow of water through said second heat exchanger; a burner coupled to heat said water in said boiler; a first thermostat for detecting the temperature in said first zone coupled to said first remotely controlled valve, said water circulation pump and said burner; a second thermostat for detecting the temperature in said second zone coupled to said second remotely controlled valve, said water circulation pump and said heating means; and delay means preconditioned to pass a signal from 10 to 50 20 minutes after activation interposed between said second thermostat and said burner to delay the operation of said burner after operation of said second thermostat and said second remotely controlled valve and water circulation pump.

55 9. A zone temperature control system comprising a
first zone; a first heat exchanger in said first zone; a sec-
ond zone; a second heat exchanger in said second zone;
a third zone; a third heat exchanger in said third zone;
60 a fluid moving means; means coupled to said fluid moving
means to feed a fluid along a first path to said first
heat exchanger, along a second path to said second heat
exchanger and along a third path to said third heat ex-
changer; first fluid control means to control the flow of
65 the fluid through said first heat exchanger; second fluid
control means to control the flow of the fluid through
said second heat exchanger; third fluid control means to
control the flow of the fluid through said third heat ex-
changer; heating means to heat said fluid; a first tempera-
70 ture sensitive means for detecting the temperature in
said first zone coupled to said first fluid control means,
said fluid moving means and said heating means; a sec-
ond temperature sensitive means for detecting the tem-
perature in said second zone coupled to said second
75 fluid control means, said fluid moving means and said

heating means; a third temperature sensitive means for detecting the temperatures in said third zone coupled to said third fluid control means, said fluid moving means and said heating means; first delay means interposed between said second temperature sensitive means and said heating means to delay the operation of said heating means for a preselected interval of time after operation of said second thermostat and said second remotely controlled valve and water circulation pump; and second delay means interposed between said third temperature sensitive means and said heating means to delay the operation of said heating means for a preselected interval of time after operation of said third thermostat and said third remotely controlled valve and water circulation pump.

10. A zone temperature control system comprising a first zone; a first heat exchanger in said first zone; a second zone; a second heat exchanger in said second zone; a third zone; a third heat exchanger in said third zone; a fluid moving means; means coupled to said fluid moving means to feed a fluid along a first path to said first heat exchanger, along a second path to said second heat exchanger and along a third path to said third heat exchanger; first fluid control means to control the flow of the fluid through said first heat exchanger; a second fluid control means to control the flow of the fluid through said second heat exchanger; third fluid control means to control the flow of the fluid through said third heat exchanger; heating means to heat said fluid; a first temperature sensitive means for detecting the temperature in said first zone coupled to said first fluid control means, said fluid moving means and said heating means; a second temperature sensitive means for detecting the temperature in said second zone coupled to said second fluid control means, said fluid moving means and said heating means; a third temperature sensitive means for detecting the temperature in said third zone coupled to said third fluid control means, said fluid moving means and said heating means; first delay means preconditioned to pass a signal from 10 to 20 minutes after activation interposed between said second temperature sensitive means and said heating means to delay the operation of said heating means after operation of said second thermostat and said second remotely controlled valve and water circulation pump; and second delay means preconditioned to pass a signal from 10 to 20 minutes after activation interposed between said third temperature sensitive means and said heating means to delay the operation of said heating means after operation of said third thermostat and said third remotely controlled valve and water circulation pump.

11. A zone temperature control system comprising a first zone; a first heat exchanger in said first zone; a second zone; a second heat exchanger in said second zone; a third zone; a third heat exchanger in said third zone; a fluid moving means; means coupled to said fluid moving

5 means to feed a fluid along a first path to said first heat exchanger, along a second path to said second heat exchanger and along a third path to said third heat exchanger; first fluid control means to control the flow of the fluid through said first heat exchanger; second fluid control means to control the flow of the fluid through said second heat exchanger; third fluid control means to control the flow of the fluid through said third heat exchanger; heating means to heat said fluid; a first temperature sensitive means for detecting the temperature in said first zone coupled to said first fluid control means, said fluid moving means and said heating means; a second temperature sensitive means for detecting the temperature in said second zone coupled to said second fluid control means, said fluid moving means and said heating means; a third temperature sensitive means for detecting the temperature in said third zone coupled to said third fluid control means, said fluid moving means and said heating means; delay means fed by said second temperature sensitive means and said third temperature sensitive means coupled to delay the operation of said heating means for a preselected interval of time.

15. A zone temperature control system comprising a first zone; a first heat exchanger in said first zone; a second zone; a second heat exchanger in said second zone; a third zone; a third heat exchanger in said third zone; a fluid moving means; a means coupled to said fluid moving means to feed a fluid along a first path to said first heat exchanger, along a second path to said second heat exchanger and along a third path to said third heat exchanger; first fluid control means to control the flow of the fluid through said first heat exchanger; second fluid control means to control the flow of the fluid through said second heat exchanger; third fluid control means to control the flow of the fluid through said third heat exchanger; heating means to heat said fluid; a first temperature sensitive means for detecting the temperature in said first zone coupled to said first fluid control means, said fluid moving means and said heating means; a second temperature sensitive means for detecting the temperature in said second zone coupled to said second fluid control means, said fluid moving means and said heating means; a third temperature sensitive means for detecting the temperature in said third zone coupled to said third fluid control means, said fluid moving means and said heating means; a delay means fed by said second temperature sensitive means and said third temperature sensitive means coupled to delay the operation of said heating means for a preselected interval of time.
